UNITED STATES PATENT OFFICE

137,971

DESIGN FOR A ROCKING HORSE

Walter A. Hartwig, West Allis, Wis.

Application February 2, 1944, Serial No. 112,410

Term of patent 14 years

(Cl. D34—15)

To all whom it may concern:

Be it known that I, Walter A. Hartwig, a citizen of the United States, residing at West Allis, in the county of Milwaukee and State of Wisconsin, have invented a new, original, and ornamental Design for a Rocking Horse, of which the following is a specification, reference being had to the accompanying drawing, forming part thereof.

The drawing is a perspective view of a rocking horse, showing my new design.

I claim:

The ornamental design for a rocking horse, as shown.

WALTER A. HARTWIG.
